UNITED STATES PATENT OFFICE.

WILLIAM A. CARPENTER, OF CHARLOTTE, NORTH CAROLINA, ASSIGNOR OF ONE-FOURTH
TO JESSE B. CARPENTER, OF CHARLOTTE, NORTH CAROLINA.

MAIL-BAG.

No. 928,106.

Specification of Letters Patent.

Patented July 13, 1909.

Application filed July 14, 1908. Serial No. 443,438.

To all whom it may concern:

Be it known that I, WILLIAM A. CARPENTER, a citizen of the United States, residing at Charlotte, in the county of Mecklenburg 5 and State of North Carolina, have invented new and useful Improvements in Mail-Bags, of which the following is a specification.

This invention relates to mail bags and one of the principal objects of the same is to 10 simplify the construction of the mouth of a bag and to provide improved means for supporting the bag upon an assorting rack.

Another object of the invention is to provide means for dispensing with the ordinary 15 padlock for locking the mouth of the bag and to provide an improved lock which will operate automatically upon closing the bag and which can be quickly unlocked by a key.

Still another object of the invention is to 20 provide a mail bag with supporting loops for supporting the bag upon an assorting rack.

These and other objects may be attained by means of the construction illustrated in 25 the accompanying drawing, in which:—

Figure 1 is a side elevation of the upper part of a mail bag made in accordance with my invention, the mouth of the bag being closed. Fig. 2 is a plan view looking down into the open mouth of the bag. Fig. 3 is a 30 perspective view of one of the lock plates. Fig. 4 is a similar view of the other lock plate. Fig. 5 is a detail section of the lock. Fig. 6 is an inside elevation of three of the mouth plates of the bag. Fig. 7 is a similar view of 35 the other three plates forming the mouth of the bag. Fig. 8 is a plan view of the mouth plates of the bag closed.

Referring to the drawing for a more specific description of my invention, the numeral 1 designates a mail bag of the usual or 40 any preferred construction and connected to the open end or mouth of the bag are the three male mouth plates 2 and the three female mouth plates 3. The plates 2 are each provided with a rib or projection 4 and upon 45 the ends of said plate are knuckles or pintle bearings 5 adapted to be connected to the knuckles or bearings 6 upon the opposite ends of said plate by means of suitable pintles 7. The plates 2 are secured to the mouth of the bag by means of suitable plates 8 disposed upon the inside of the bag mouth while the plates 2 are disposed upon the outer side thereof and rivets 9 are passed

through the plates 8, the bag 1 and the 55 plates 2.

The female mouth plates 3 are each provided with spaced ribs or projections 4^a between which a groove 5^a is provided for the rib or projection 4 upon the male members 2. 60 It is to be noted that the ribs or projections 4 are rounded off at their ends as at 5^a and that the female members 3 are similarly rounded off as at 6^a, thus permitting the members 2 and 3 to close together tightly and to form a 65 practically smooth unbroken upper surface with interlocking parts. Connected to each of the pintles 7 is a wire supporting loop 10, said loops adapted to be connected to suitable hooks on the assorting rack. The inner 70 ends of the loop are seated in notches 11 formed in the end of the sections 2 and 3. The loops 10 are disposed between the pintle bearings 5 and 6 on the members 2 and 3. The female members 3 are secured to the 75 mouth of the bag by means of the plates 8^a in a manner similar to that of the members 2.

The oppositely disposed locking sections of the bag mouth are in every way similar to the other members excepting that the male 80 member is provided with a recess 12 and that the plate 8^c is provided with a recess 13 in which the lock casing 14 is seated when the bag is locked. Within the casing 14 a sliding bolt 15 is mounted, said bolt comprising 85 spaced legs 16 each provided with a lug 17. An enlargement 18 on the bolt 15 serves as an abutment for a spring 19, which normally holds the bolt 15 projected. The head of the bolt 15 is beveled so that when the rib or 90 projection 4 is closed into the groove 5^a the bolt will automatically catch into the recess 12. A key hole 20 is provided in the female lock plate and a key inserted in said key hole and turned in either direction will come in 95 contact with the lug 17 and withdraw the bolt 15 from the recess 12.

From the foregoing it will be obvious that my mail bag is of simple construction, dispenses entirely with a padlock, is provided 100 with means for supporting the bag on a rack, is strong durable and efficient and can be manufactured at low cost.

Having thus described the invention, what is claimed as new, is:—

A mail bag comprising mouth plates pivotally connected together, oppositely disposed lock plates pivotally connected to ad-

jacent mouth plates, one of said lock plates being provided with a rib having a bolt recess therein, the other plate having a pair of spaced ribs with an intermediate groove, one 5 of said grooves having a recess in line with the recess in the rib of the companion plate, a sliding bolt, a spring for holding said bolt normally projected into said recesses, said bolt having spaced arms provided with lugs,

and an enlarged lug on the bolt against 10 which said spring bears.

In testimony whereof I affix my signature in presence of two witnesses.

WILLIAM A. CARPENTER.
